HOUSEHOLD STILL FOR DRINKING WATER AND THE LIKE

Gary A. Gerber, Bridgeport, Conn., assignor to American
Machine & Foundry Company, a corporation of New
Jersey

Filed Jan. 28, 1963, Ser. No. 73,335

Term of patent 14 years

(Cl. D16—2)

FIG. 1

FIG. 2

FIGURE 1 is a front perspective view of a household still for drinking water and the like showing my new design.

FIGURE 2 is a perspective view taken from the rear of FIGURE 1.

The cord member disclosed in FIGURES 1 and 2 is broken away to indicate indeterminate length.

I claim:

The ornamental design for a household still for drinking water and the like, as shown and described.
